CAPPING MACHINE

Ralph B. Bagby, Evanston, Ill., assignor to Triangle Package Machinery Company, Chicago, Ill., a corporation of Illinois

Application November 20, 1948, Serial No. 61,254

4. Claims. (Cl. 226—92)

1

The present invention relates to capping machines and more particularly to machines for installing covers on containers. Machines of this type may be used for installing various types of covers on different kinds of containers. Where the container is made of paper or similar lightweight material difficulties are frequently encountered in firmly seating the cover without collapsing the container. This is the case particularly where the container is provided with an internal cap seat in the form of a groove positioned below the lip of the container.

It is, therefore, an object of the present invention to provide a capper which will firmly install covers on containers while applying a minimum amount of pressure to the cover and container.

It is another object to provide a capper in which the caps are moved individually into position for installation.

It is a further object to provide a capper which will install a cap with a minimum amount of pressure on a cap seat positioned below a restricted throat in the container and which has a smaller diameter than the cap.

It is another object to provide a capper wherein caps are individually fed into position for installation from a source of supply in which springs or similar means are not required to maintain the caps in position for feeding.

With these and various other objects in view, the invention may consist of certain novel features, as will be more fully described and particularly pointed out in the specification, drawings and claims appended hereto.

In the drawings, in which like reference characters are used to designate like parts—

Figure 1 is a fragmentary elevation showing a capper embodying the invention in one position of its cycle;

Figure 2 is a top plan view of the capper shown in Figure 1;

Figure 3 is a sectional elevation showing the capper in another position of its cycle; and

Figure 4 is a sectional view taken on the line 4—4 of Figure 3.

In the drawings, a hand operated capper is shown mounted on a top plate 12 which may be supported in any suitable manner, such as by end plates 14 and a back plate 16. Top plate 12 has an opening through which a rising table 18 may move. The table is flush with the top plate when in its lowered position, as shown in Figure 1. The table is shown in its elevated position in Figure 3. Table 18 is provided with a down-

wardly extending slide 20 which is mounted in the guides 22 secured to the back plate 16.

Table 18 is raised and lowered by moving lever 24 which is connected by links to the lower end of slide 20. Any means, manual or power operated, may be used for raising and lowering table 18. The machine is particularly suited for operation in conjunction with a container dispenser and filler, in which event the table actuating mechanism may be driven by and synchronized with the dispenser.

Shaft 26 is mounted in bearings 28 secured to the under surface of top plate 12. Hand lever 24 is mounted on shaft 26 which is connected by arm 30 and link 32 to one end of rocker 34. Bearings 36 which support rocker 34 are secured to the under surface of top plate 12. Link 38 connects the other end of rocker 34 to slide 20. Downward movement of hand lever 24 raises table 18 to the position shown in Figure 3.

A post 40 is mounted on top plate 12 and has a laterally extending supporting arm 42 on which the upper end of plunger rod 44 is supported. A spring 43 is positioned on the plunger rod 44 between the top of sleeve 48 and supporting arm 42. The plunger is secured to supporting arm 42 by a nut 47 and washer 45 and is permitted slight vertical movement with respect to the arm. The spring tends to absorb vibration in the event the sleeve is moved upwardly against yoke 46 an excess amount but, for the purposes of operation, it may be said that plunger 44 is mounted in fixed relation to arm 42. Feed cap yoke 46 is mounted on plunger rod 44 in fixed relation thereto.

The capper body having a sleeve 48 is slidably mounted on the plunger rod 44. The lower end of sleeve 48 is provided with a spider 50 to which the capper bell 52 is secured by screws 54. Adjacent spider 50 and, in the present embodiment, cast integrally with it, is cap tube 56. Adjacent the bell 52, and in part underlying the cap tube 56, the guide member 58 provides a track and support for slide 60.

Slide cranks 62 are pivotally supported on the upper portion of cap tube 56 by the pivot screws 66. The cranks are pivotally connected by links 68 to the ends of cap feed yoke 46. The lower ends of the cranks are connected to cap slide yoke 70 through links 72.

Guide member 58, which is shown in cross section in Figures 3 and 4, extends under cap tube 56 and provides the support on which the caps 74 rest. A longitudinal slot 76 extends the length of the member which is provided with offset por-

tions 78 in its under face on both sides of the slot to accommodate the flanges 80 on slide 60. It is also provided with similar offset portions 82 in its upper surface to accommodate the flanges 84 on cap slide plate 86. Cap slide 60 is secured to slide yoke 70 by screw 88. Slide plate 86 is secured to slide 60 by screws 90.

As shown in Figures 2 and 3, the forward end 92 of slide plate 86 projects beyond the flanges 84. The upper surface of this projection 92 is lower than the upper surface of the main portion of the slide plate 86 and provides a shoulder 94 where it joins the main portion of the slide plate 86. This upper surface of projection 92 slopes downwardly toward its forward end to the extent that it is below the plane of the upper surface of guide member 58. The depth of offset portion 94 is less than the thickness of a single cap which the machine is designed to install. The rear portion of the upper surface of guide plate 86 is above that of the upper surface of guide member 58.

In the embodiment of the invention shown, the lower end of plunger 44 is provided with a disc 96 which has a centrally disposed button or projection 98 secured to its under face. It is contemplated, however, that the disc may be tapered or provided with other means for reducing the diameter of the cap when being seated, all of which will become more apparent as the operation of the machine is described.

In operation, the capper is initially in the position shown in Figure 1, with caps 74 in cap tube 56 which is provided with a cut-out portion 106 to accommodate the pull-tabs on the caps. In the event the container is made of such lightweight material as to have a tendency to collapse when being capped, a lifter may be provided to remove some of the pressure from the container. The lifter 108 shown in Figures 1 and 3 is a vertical member mounted on the rising table 18 and positioned to engage the outer flange of capper bell 52 when the table 18 is raised. The length of the lifter 108 is such that it engages the bell at approximately the same time as the rim 102 of cup 100 engages the annular offset portion 110 of bell 52 when table 18 is raised.

In order to move a cap from tube 56 into position for capping, hand lever 24 is moved in the counter-clockwise direction which, in turn, moves arm 30 and link 32 which cause the connected end of rocker 34 to move downwardly. The other end of rocker 34 moves upwardly and, through link 38, moves slide 20 upwardly in guides 22, together with table 18. Lifter 108 engages the outer edge of bell 52 which, through spider 50, moves sleeve 48 upwardly on plunger rod 44, together with guide 58 and tube 56.

Slide cranks 62 are likewise moved upwardly and the bottoms of lost-motion slots 112 engage screws 114 on links 68. Continued upward movement causes the lower ends of cranks 62 to move outwardly and, through links 72, move slide yoke 70 and slide 60 with slide plate 86. As slide plate 86 moves from the position shown in Figure 1 to that shown in Figure 2, it passes through cap tube 56 under the caps 74. Stop member 116 on guide 58 engages slide yoke 70 at approximately the same time that sleeve 118 reaches feed cap yoke 46.

When hand lever 24 is moved in the clockwise direction, the movement of the various parts previously described is reversed. As the capper is lowered by the table, the lost-motion slots 112 enable the capper bell 52 and cap tube 56 to be

lowered to some extent with respect to disc 96 before slide plate 86 starts to move. The sloping end 92 of slide plate 86 being below the upper surface of guide member 58 on which caps 74 are supported, is underneath the bottom cap. As the slide plate is moved toward the caps, the latter are raised by the sloping end 92 of the slide plate until offset portion 94 engages the edge of the bottom cap. Continued movement of the slide plate moves the bottom cap into the annular groove 120 between spider 50 and bell 52 where it is supported in position for installation.

The depth of the offset portion 94 being less than the thickness of a single cap, only one cap 15 will be moved by the slide plate. The height of the sloping portion 92 adjacent the offset portion 94 being greater than that of the upper surface of guide member 58, the cap will be raised by the slide plate and the weight of a cap or stack of 20 caps will prevent the bottom cap from riding up over the offset portion 94. The slot 122 at the bottom of the side wall of cap tube 56, which permits the bottom cap to be moved from the tube into groove 120, is of such a height that only 25 one cap can be moved through it at the same time.

Stop member 124 on guide 58 is positioned to engage slide yoke 70 at the same time as the cap 30 is completely seated in groove 120, preventing slide plate 86 from crushing it against the walls 35 of the groove.

A container or cup 100 may be placed on rising table 18 manually or by suitable conveyor apparatus. The cup shown has a beaded or rolled 35 lip 102 and an annular cap seat 104 in the form of a groove spaced from the lip. As hand lever 24 is moved downwardly, container 100 is moved upwardly into cap bell 52. The mouth of the bell positions the container so that lip 102 engages offset portion 110 of the bell. At approximately the same time, lifter 108 engages the outer portion of the bell.

Continued upward movement of table 18 moves the capper and cup to the point where the cap 45 in groove 120 engages the under surface of disc 96. In the meantime, slide plate 86 has been moved outwardly so that the sloping end is not engaged by the disc 96. The cap is moved out of groove 120 by the disc and the container is 50 moved upwardly until the cap is seated, as shown in Figure 3.

Cap seat 104 has a greater diameter than the mouth of the container, as does the cap, and it is therefore necessary to use a certain amount of 55 pressure to force the cap past the restricted mouth of the container. The pressure of button 98 on the cap causes it to assume the contour of a portion of the surface of a sphere, thereby reducing its diameter and permitting it to pass through the restricted mouth of the container with a minimum amount of pressure. As the container is lowered from the disc, the cap then assumes its original shape and fits tightly in the cap seat. During the lowering movement of the capper, slide plate 86 moves another cap into 60 groove 120, as previously described. The disc 96 may be shaped otherwise than shown to displace the central portion of the cap sufficiently to reduce its diameter when it engages the cap.

It is to be understood that this invention is 70 not to be limited by the exact embodiment of the device shown, which is merely by way of illustration and not limitation, as various other forms of the device will be apparent to those skilled in the art without departing from the 75

spirit of the invention or the scope of the claims.

I claim:

1. A container capper having a plunger, a support for said plunger, a cap supply tube slidably mounted on said plunger, a disc on said plunger, a rising table for moving a container toward said disc, a lifter extending upwardly from the table for sliding said cap supply tube upwardly when said container is moved toward said disc, and a slide for moving a cap from said cap supply tube to a position between said disc and said container when said rising table is moved to its lowered position.

2. A container capper having a plunger, a support for said plunger, a cap supply tube slidably mounted on said plunger and having caps therein, a disc on said plunger, a rising table for moving a container toward said caps, a lifter extending upwardly from the table and above the container for sliding said tube upwardly, a slide on said tube, actuating members for said slide connected to said plunger and said slide for moving said slide under said caps when said holder is being raised and for causing said slide to engage the bottom cap and move it to a position between said disc and a container when said holder is lowered.

3. In a container capper, a support, a cap-seating member mounted in fixed relation to said support, a cap supply tube vertically movable with respect to said support, a guide underlying said tube, a slide mounted in said guide for lateral movement with respect to said tube, said slide having a sloping portion, the end of which is below the plane of the floor of said tube, a 35

shoulder on said slide adjacent said sloping portion extending above the plane of said floor, a cap holder adjacent to and movable with said tube in vertical alignment with said cap-seating member, a crank having its fulcrum vertically movable with said tube having one end secured to said slide and the other end pivotally secured in fixed relation to said support, and a table for lifting a container to receive a cap, said table carrying a lifter for raising said supply tube.

5 4. In a container capper, a unit slidably mounted on a vertical stationary shaft comprising a cap supply tube, a cap holder adjacent said tube, a slot connecting said tube and holder, a guide underlying said tube, a slide mounted in said guide, a crank pivotally mounted on said unit and operatively connected to said slide and said shaft, a table for lifting a container to receive a cap and a lifter carried by said table for raising and lowering said unit on said shaft, said slide moving a cap from said tube through said slot into the cap holder when the unit is lowered.

20 RALPH B. BAGBY.
